W. JAMES.
CARBURETER.
APPLICATION FILED SEPT. 6, 1917.

1,283,784.

Patented Nov. 5, 1918.

FIG.1.

FIG.2.

UNITED STATES PATENT OFFICE.

WILLIAM JAMES, OF BIRKENHEAD, ENGLAND.

CARBURETER.

1,283,784.

Specification of Letters Patent.

Patented Nov. 5, 1918.

Application filed September 6, 1917. Serial No. 190,021.

To all whom it may concern:

Be it known that I, WILLIAM JAMES, a subject of the King of England, and residing at Birkenhead, in the county of Lancaster, England, have invented Improvements in Carbureters for Internal-Combustion Engines and the like, of which the following is a specification.

My invention relates to improvements in apparatus for atomizing a liquid fuel, such as oil, and intimately mixing the same with air, for carbureting the air.

An important object of the invention is to provide apparatus of the above mentioned character, which is highly efficient in operation, simple in construction, strong and durable.

In the accompanying drawings forming a part of this specification, and in which like numerals are employed to designate like parts throughout the same,

Figure 1 is a central vertical longitudinal section through a carbureter embodying my invention, parts being shown in elevation,

Fig. 2 is a transverse section taken on line 2-2 of Fig. 1.

In the drawings, wherein for the purpose of illustration is shown a preferred embodiment of my invention, the numeral 1 designates a float chamber receiving the liquid fuel, such as oil, and discharging the same through a port 2. The numeral 3 designates a main chamber, the lower end of which is equipped with a coupling 4. The port 2 discharges into the coupling 4, as shown. The main chamber 3 is provided upon one side with an air inlet 5.

Extending vertically into the main chamber 3 is an inner air supply tube 6, the lower end of which is secured to a coupling 7, screw-threaded into the lower end of the coupling 4. The inner air supply tube 6 is surrounded by an outer oil supply tube 8, the internal diameter of which is slightly greater than the external diameter of the tube 6, thereby providing an annular space 9.

The upper end of the outer tube 8 carries an enlarged hollow head or nozzle 10, the upper end of which is closed, but preferably spherically curved. The lower end of the nozzle 10 is also spherically curved for receiving a deflector 11, the lower portion of which is spherically curved, providing an outlet passage 12 as shown. The deflector 11 is slightly spaced above the inner tube 6,

and is held in place by webs 13, secured thereto and to the nozzle 10. The nozzle 10 has apertures 14 formed therein and arranged between the webs 13.

The top of the main chamber 3 is provided with an upwardly extending neck 15, receiving a tubular coupling 16, adapted for connection with the cylinder of the engine, and constituting the outlet of the carbureter. Arranged within the tubular coupling 16 is a pivoted throttle valve 17, opened and closed for controlling the passage of carbureted air to the engine.

The numeral 18 designates a sleeve, surrounding the nozzle 10 and screw-threaded into the coupling 16, as shown at 19. The sleeve 18 serves to deflect the upwardly ascending current of air in proximity to the nozzle 10.

The operation of the carbureter is as follows:

The oil or liquid fuel from the chamber 1 passes through the port 2 and upwardly through the space 9, discharging from the upper end thereof in proximity to the upper end of the air tube 6. The suction from the cylinders draws the air upwardly through the tube 6 and as this air discharges from the upper end of the tube 6 it atomizes and takes up the liquid fuel discharging from the upper end of the passage 9. The air containing the more or less atomized liquid fuel passes about the deflector 11 through the passage 12 and is guided near the inner wall of the nozzle 10, to pass upwardly therein. This air, at the upper end of the nozzle 10 is deflected downwardly by the spherically curved portion, and travels inwardly of the ascending portions of the air. The descending current at the top of the deflector 11 passes horizontally through the openings 14, and in so doing passes through the upwardly moving portion of the air. It is thus apparent that an intimate mixture of the atomized oil and air is effected. The carbureted air passing through the opening 14 enters the sleeve 18, and becomes mixed with the ascending current of air, forming a charge which is fed to the cylinders of the engine.

It is to be understood that the form of my invention herewith shown and described is to be taken as a preferred example of the same, and that various changes in the shape, size, and arrangement of parts, may be resorted to, without departing from the

spirit of my invention or the scope of the subjoined claims.

Having thus described my invention what I claim is:

- 5 1. In a carbureter of the character described, a substantially vertical air supply tube, an outer tube surrounding the air supply tube in spaced relation to form an annular passage therewith, means for supplying a liquid fuel into the passage, a nozzle carried by the upper end of the outer tube and having its upper and lower portions 25 spherically curved, with the upper spherically curved portion closed, said nozzle having transverse openings in its side arranged near the lower spherically curved portion thereof, a deflector arranged within the lower 30 spherically curved portion of the nozzle beneath the transverse opening, and an air passage surrounding the nozzle.
- 10 2. In a carbureter of the character described, a substantially vertical air supply tube, an outer tube surrounding the air sup-
- 15 20

ply tube in spaced relation to form an annular passage therewith, means for supplying a liquid fuel into the passage, a nozzle carried by the upper end of the outer tube and having its upper and lower portions 25 spherically curved, with the upper spherically curved portion closed, said nozzle having transverse openings in its side arranged near the lower spherically curved portion thereof, a deflector arranged within the lower 30 spherically curved portion of the nozzle beneath the transverse opening, and an air passage surrounding the nozzle.

In testimony whereof I have signed my name to this specification in the presence of 35 two subscribing witnesses.

WILLIAM JAMES.
